ABSTRACT

A luminous diode protecting device, which comprising a circuit containing a luminous diode and a means being connected with said luminous diode and being capable to keep the voltage supplied to said luminous diode in an inverse direction under the reverse withstanding voltage of said luminous diode.

PROTECTIVE DEVICE FOR A LUMINOUS DIODE

The present invention relates to a protective device for a luminous diode.

A luminous diode is used for indication purpose in various instruments or as a head for optical recording in a video-disc. Because its reverse withstand voltage is not sufficiently high, such luminous diode as used in a conventional manner has a shortcoming that it may be damaged when alternating current is used, or when reverse voltage is impressed by an error, or when the voltage which has been given to other circuit is momentarily impressed as reverse voltage, etc.

The present invention is to provide a protective device for a luminous diode, by which damages to a luminous diode is prevented.

Another object of the present invention is to provide a luminous diode protective device, which contains such diode as being provided in series with or in parallel with the luminous diode for preventing damages to the luminous diode.

FIG. 1 is a circuit diagram wherein the protective device shown in Example 1 of the present invention is adopted.

FIG. 2 is a circuit diagram showing Example 2 of the present invention.

FIG. 3 is a circuit diagram showing Example 3 of the present invention.

FIG. 4 is a circuit diagram showing Example 4 of the present invention.

FIG. 1 shows a case when the luminous diode protective device of the present invention is adopted in a device to drive and control a cine-camera C by a remote control unit V, and S₁ is a release switch of a cine-camera C, and S₂ is a release switch for a cine-camera C being provided at the remote control unit V. L is a load such as a motor, a magnet, a resistances, etc., and B₁ is a high voltage power source of, for example, 6 volts, while B₂ is a low voltage power source of, for example, 3 volts. D_e is a luminous diode which emits light by placing the switch S₂ in "on" state, and R is its load resistance. In this case the cine-camera C is controlled by the switch S₂, and its state is confirmed by the luminous diode D_e. When the switch S₂ is in "off" state the power source B₁ and the power source B₂ are impressed on the luminous diode D_e through the load L and the resistance R, thus there is such possibility that the luminous diode D_e may be damaged, therefore a diode D is connected in parallel with the luminous diode D_e in a reverse polarity.

While in the Example 1 shown in FIG. 1 the diode D is connected in parallel with the diode D_e in an inverse direction, the diode D may be connected in series with the luminous diode D_e in an ordinary direction.

Now, explanations shall be made on an example 55

wherein a diode D is connected in series with a luminous diode D_e referring to FIG. 2, in which a diode D is connected in series with a luminous diode D_e. R' is a resistor being connected in parallel with the luminous diode D_e. Reverse voltage working on the luminous diode will flow through the diode D and a resistance R', thus the luminous diode D_e can escape from being damaged.

FIG. 3 shows a case wherein a luminous diode D_e' is used in place of the diode D in the Example 1 shown in FIG. 1. The luminous diode D_e' will protect the luminous diode D_e when reverse voltage works on the luminous diode D_e, and at a same time it indicates the fact that reverse voltage is working. When an alternating current power source AC is connected in place of the direct current power source B₂ in Example 3, flashing indication can be obtained.

Example 4 of FIG. 4 shows a case when a light receiving diode PD is connected in place of the diode D in Example 1. In this Example 4 the light receiving diode PD protects the luminous diode D_e, and at a same time receives the light emitted by the diode D_e and gives counter bias to the luminous diode D_e to turn off the same. Said counter bias is put off as the luminous diode D_e is turned off, then the luminous diode is lighted again. That is, it is attenuatingly oscillated. In the event it is intended to simply oscillate the same, a photoresistance element may be used in place of the light receiving diode.

Since the present invention has the above-mentioned arrangement even when reverse voltage works on the luminous diode D_e, it is protected by the diode D, etc.

What is claimed is:

1. An apparatus for energizing and protecting a luminous diode, comprising diode means connected in parallel with said luminous diode, a resistance connected in series with said luminous diode and with said diode means, and circuit means for applying a current through said resistance and said diode means as well as said luminous diode, said diode means exhibiting a voltage drop thereacross less than the maximum inverse voltage which the luminous diode can withstand when said circuit means applies an inverse voltage across the luminous diode.

2. An apparatus as in claim 1, wherein said diode means is poled in a direction reverse to that of said luminous diode.

3. An apparatus as in claim 2, wherein said diode means is a luminous diode.

4. An apparatus as in claim 3, wherein said diode means is a light receiving diode.

5. An apparatus as in claim 4, wherein said light receiving diode receives light from said luminous diode.
